UNITED STATES PATENT OFFICE.

PAUL MONTGOMERY DAVIS, OF CHICAGO, ILLINOIS.

REFRIGERATOR.

Application filed July 23, 1923. Serial No. 653,364.

To all whom it may concern:

Be it known that I, PAUL MONTGOMERY DAVIS, a citizen of the United States, and a resident of Chicago, in the county of Cook 5 and State of Illinois, have invented a new and useful Improvement in Refrigerators, of which the following is a full, clear, and exact description.

My invention relates to improvements in refrigerators, and it consists in the combinations, constructions, and arrangements herein described and claimed.

The ordinary refrigerator consists of a receptacle, having heat insulated walls and 15 containing an ice compartment which cools air that subsequently flows to the lower compartment, containing the food or other articles to be kept in a cool state. The water from the melting ice is ordinarily 20 permitted to escape from the refrigerator while the ice is melted. This water is practically at a freezing temperature, and in itself would form a medium for keeping articles cold.

An object of my invention is to conserve 25 this cold water which would otherwise be wasted.

A further object of my invention is to provide a refrigerator in which the heat 30 insulating means is cold water which surrounds the food retaining compartment.

A further object of my invention is to provide a refrigerator of the type described, which is simple in construction and which 35 requires a smaller amount of ice to keep it at a given temperature, than refrigerators of the type in which the food holding receptacle is cooled by air which is chilled by the ice in the upper chamber.

Other objects and advantages will appear 40 in the following specification, and the novel features of the invention will be particularly pointed out in the appended claim.

My invention is illustrated in the accompanying drawings, forming part of this 45 application, in which—

Figure 1 is a section along the line 1—1 of Figure 2,

Figure 2 is a section along the line 2—2 50 of Figure 1,

Figure 3 is a section along the line 3—3 of Figure 1, and

Figure 4 is a perspective view of the water 55 receptacle.

In carrying out my invention, I provide an exterior casing, consisting of side walls

1, a bottom 2, the rear wall 3, and the front wall 4'. These walls are preferably of wood.

Disposed within the casing 1 is an inner 60 metal casing, having outer walls 4, sides and bottom, and rear and inner walls 5 spaced therefrom. As will be seen from the drawings, a water space 6 is provided between the walls 4 and 5, along the sides, 65 rear and bottom of the metal casing.

Secured to the outer walls 1, on the inner face thereof, are cleats 7, having notches 8 to receive cross bars 9, by which the ice may be supported. In order to retain the melted 70 ice at the top of the inner casing, I provide a removable pan or tray like that shown in Figure 4. In this figure, it will be observed that the forward part of the tray is provided with an upwardly extending front 75 portion 11, which is integral with sides 12, the latter being bent back upon themselves, as shown at 12'. Similarly, a back portion 13 has portions 13' which are bent back upon themselves. At the center is a cut-away 80 portion 14. The bent-over portions 12' and 13' are arranged to rest on the upper edges of the inner metal walls 5, so as to support the water tray in the position shown in 85 Figure 2.

A drain pipe 15 is provided, which extends to a point level with the edge of the cut-away portion 14, and which passes through the bottom 2, where it may empty 90 into a drain funnel 16, or other suitable means for carrying out water.

The top of the ice compartment may be provided with a cover 17 arranged to fit snugly at the top of the outer casing 1, and this cover may be hinged or not, as 95 desired.

From the foregoing description of the various parts of the device, the operation thereof may be readily understood. When the cover 17 is removed for placing in ice, 100 there will be no down draft created, as in the case of the ordinary refrigerator, should one of the food compartment doors be open or slightly ajar, since there is no communication between the ice chamber and the food chamber. The latter may be provided with shelves 18 for retaining articles of food thereon. A door 19 permits access to the interior of the food compartment.

The water from the ice will at first fill 110 the water pan up as far as the bottom of the cut-away portion 14, and therefore it

will run over into the space 6 between the inner and outer walls of the metal inner casing, and will eventually fill up to the top of the overflow pipe 15. Further melting of the ice will cause water to run out at the top of the drain, but this water is the warmer water which has absorbed the heat from the food-retaining compartment, and which therefore aids in keeping the latter cool. The colder water from the melting ice will flow immediately downward, after passing the cut-away portion 14, and the cold water will entirely surround the food compartment. Thus the cold water from the melting ice is utilized, where it would otherwise be wasted. A given quantity of ice will therefore last a much longer time in this refrigerator, than in one in which the ice cold water is permitted to flow out immediately.

Obviously the outer walls 1 could be pro-

vided with air insulation or packing, if desired, without departing from the spirit or the scope of the invention.

I claim:

The combination, with an outer casing, of an inner metal casing, having double walls and a water-tight bottom, the space between said walls constituting a water-retaining chamber, a metal water pan having portions bent back to form hooks for suspending the water pan on said inner casing, said water pan having an overflow outlet communicating with said water-retaining chamber, means for supporting ice over said water pan, said means being disposed so as to permit the drip to fall into said water pan, and a drain pipe having its upper end level with the overflow from said water pan.

PAUL MONTGOMERY DAVIS.
